UNITED STATES PATENT OFFICE

93,705

DESIGN FOR A CABINET

Ira Copeland, Detroit, Mich., assignor to American Show Case & Manufacturing Company, a corporation of Michigan

Application April 6, 1933, Serial No. 47,705

Term of patent 14 years

To all whom it may concern:

Be it known that I, IRA COPELAND, a citizen of the United States, residing at 24 Colorado Avenue, in the city of Detroit, county of Wayne, and State of Michigan, have invented a new, original, and ornamental Design for Cabinets, of which the following is a specification, reference being had to the accompanying drawings, forming part thereof.

Figure 1 is a front elevation with the cabinet in open or extended position;

Figure 2 is a front elevation with parts thereof in closed position;

Figure 3 is a top plan view with the cabinet in open or extended position;

Figure 4 is a side elevation with the cabinet in open or extended position;

Figure 5 is a side elevation with parts in closed position; and

Figure 6 is a perspective view taken in front of and somewhat above the bar section, the cabinet being in open or extended position.

The cabinet is so constructed that when in its open or extended position, hinged members are swung downwardly out of the swinging portion of the upper cabinet section to form an unbroken ledge portion over the side walls of the lower section of the cabinet.

I claim:

The ornamental design for a cabinet, as shown and described.

In testimony whereof I affix my signature.

IRA COPELAND.
